CLAIM

The ornamental design for a display screen with transitional graphical user interface, as shown and described.

DESCRIPTION

FIG. 1 is a front view of a first image in a sequence of a display screen with transitional graphical user interface for an embodiment;

FIG. 2 is a front view of a second image thereof;

FIG. 3 is a front view of a third image thereof;

FIG. 4 is a front view of a fourth image thereof;

FIG. 5 is a front view of a fifth image thereof; and,

FIG. 6 is a front view of a sixth image thereof.

The broken lines form no part of the claimed design. The outer circle in broken lines is included to show an unclaimed portion of an example display screen and forms no part of the claimed design. The portions of the transitional user interface shown in broken lines form no part of the claimed design.

The subject matter of this patent includes a process or period in which an image changes into another image to represent how an image search may be conducted. This process or period forms no part of the claimed design.

In an embodiment, the appearance of the image transitions sequentially between the images shown in FIGS. 1, 2, 3, 4, 5 and 6.
